UNITED STATES PATENT OFFICE.

JOHN W. BURNS, OF LOS ANGELES, CALIFORNIA, ASSIGNOR OF ONE-THIRD TO RUFUS A. HOLT AND ONE-THIRD TO JOSEPH W. HARASTA, BOTH OF LOS ANGELES, CALIFORNIA.

TWO-CYCLE RECIPROCATING ENGINE.

1,311,148.

Specification of Letters Patent. Patented July 22, 1919.

Application filed September 5, 1918. Serial No. 252,713.

To all whom it may concern:

Be it known that I, JOHN W. BURNS, a citizen of the United States, residing at Los Angeles, in the county of Los Angeles and 5 State of California, have invented new and useful Improvements in Two-Cycle Reciprocating Engines, of which the following is a specification.

This invention relates to a two cycle internal combustion engine, in which positively actuated valves are used to control the inlets and exhaust.

Two cycle engines are more desirable than four cycle, because of the more even flow of 10 power per stroke, a less weight of engine per unit of output, more perfect balance, and quicker acceleration. As at present constructed, the two cycle engine is less desirable than the four cycle because of its lower 15 efficiency.

It is common practice to construct two cycle gas engines with inlet and exhaust ports in each cylinder which are opened and closed by the piston. With such construction, no provision is made for adjustment of the events of a cycle. It is obvious that 20 adjustment of the events is desirable. It is an object of this invention to provide a two cycle reciprocating gas engine with positively actuated valves, which are arranged 25 so that they may be adjusted.

I accomplish these objects by means of the embodiments of my invention illustrated in the accompanying drawing, in which:

30 Figure 1 is a front elevation of a four cylinder engine constructed according to my invention. Fig. 2 is a side elevation partly in section of one of the cylinders and crank case. Fig. 3 is a section as seen on the line 35 3-3 of Fig. 2, and Fig. 4 is an enlarged fragmentary section through the piston rod at the point of its attachment to the yoke.

Referring particularly to the drawings, A are the cylinders, B the crank case, C the carburetor, D the inlet manifold, and E the 40 exhaust manifold.

The cylinders are duplicates of each other, and one will be described. Referring particularly to Figs. 2, 3 and 4, the cylinder 45 has a body 5 provided with the usual water jacket spaces. A lateral flange 6 is provided at the crank end for attachment of the cylinder to the crank case. Just above the flange is a lateral port 7, which communi-

cates with a by pass 8 extending longitudinally of the cylinder. Projecting from the cylinder opposite to the port 7 is an extension 9, which has a port 10 leading into a valve chamber formed in the extension. A plug 11 closes the valve chamber on its upper side and provides means of access to the chamber. On the lower side of the valve chamber, a valve seat is formed, and disposed thereon is a lift valve 12. On the lower side of the valve 12 is an inlet port 13 extending laterally and communicating with the inlet manifold D.

Secured on the top of the body is a cylinder head 14, in which are mounted the cylinder valves. Communicating with the bypass 8 is a passage 15, which leads to a valve chamber. Mounted in the valve chamber is a valve cage 16, which is held in position by a plug 17. The valve cage forms a seat for a valve 18. A port 19 leads to a valve chamber in which is disposed a valve cage 20. Valve cage 20 is similar to valve cage 16 and is held in position by a similar plug. Seated on the valve cage is an exhaust valve 21.

In an opening formed on the upper side of the crank case B is a rabbet 22. The cylinder is mounted upon the crank case and bolted thereto, a crank head 23 being clamped between the cylinder and case and being packed by a copper gasket 24. Formed on the crank head is a gland construction 25, through which the piston rod may pass. The body of the crank case is closed by a bottom 27 and is formed so as to be oil tight. The body is offset as indicated by 28 to form a space for the valve cams and shaft.

Disposed within the cylinder is a piston 29 provided with the usual packing and having oil ducts 30 leading from the piston rod to the periphery. A hollow piston rod 31 closed at the head end is secured to the piston and held in position by a nut 32. Perforations 33 connect the interior of the piston rod with the oil ducts 30. The piston rod extends through the gland 25 in the crank head, and is suitably packed therein. Adjacent its lower end is a dipper pipe 34, which extends laterally thereof and has its inlet pointing downwardly. A check valve 35 is mounted in the dipper pipe. The lower end of the piston rod is connected to a scotch

yoke 36, which slides on guides 37 and 38 mounted on the sides of the crank case. Slidably mounted in the slot in the yoke is a crank pin bearing 39, to which is secured a crank arm 40 on the crank shaft.

The inlet valve 12 has a stem 41, and mounted thereon is a compression spring 42, which tends to hold the valve 12 on its seat. The valve stem extends through a guide 10 plug 43 into the crank case and has a tappet 44 mounted on the lower end. The tappet rides upon a cam 45 mounted on cam shaft 46. Cam shaft 46 is operated from the engine shaft by means of intermediate gearing 15 indicated in dotted lines, and so proportioned that the ratio of gearing is one to one. This gearing may be of any well known type and is not shown in detail. Cylinder inlet valve 18 has a stem 47, which is 20 slidably mounted in the cage 16. A compression spring 48 tends to hold valve 18 upon its seat. Mounted upon the top of the cylinder head is a standard 49, upon which is pivotally mounted a lever 50 engaging the 25 valve stem 47. Engaging the other end of lever 50 is a push rod 51, which extends into the crank case and has a tappet actuated by a cam upon cam shaft 46. Exhaust valve 21 is similar in construction to the inlet valve 30 for the cylinder and operated by similar mechanism. As shown in Fig. 3, valve 21 has a valve stem 52, which is actuated by a lever 53 (see Fig. 1) mounted upon standard 49. A push rod 54 extends into the 35 crank case and is operated from the cam shaft 46.

The crank case is filled with oil, and upon each down stroke of the piston, the dipper 34 enters the oil bath, some of the 40 oil passing beyond the check valve and into the hollow piston rod. The oil then travels up the rod, through the perforations 33, into the oil ducts 30, and to the periphery of the piston.

45 Upon the up stroke of the piston, inlet valve 12 is lifted, intake valve 18 remaining upon its seat, and a charge is drawn into the cylinder below the piston. Upon the down stroke, the inlet valve 12 closes, the 50 charge is compressed below the piston, and when the latter reaches about two degrees before the end of its stroke, the intake valve 18 is opened, admitting the charge to the cylinder above the piston. The intake 55 valve 18 is closed at about eighteen degrees of the piston upstroke, and the charge compressed in the cylinder above the piston. At the beginning of the down stroke, the charge is fired, then the exhaust valve 21

opens when the piston is about 45 degrees 60 from the bottom of its stroke to permit the escape of burnt gases. Just after the intake valve is opened the exhaust valve 21 is closed. There is an overlap of the opening 65 of the exhaust and intake valves permitting scavenging.

It is obvious that the events of the stroke can be varied by adjusting the cams on the cam shaft. It is also obvious that with the use of positively actuated valve that these 70 events may be made sharp, opening and closing of the valve occurring almost instantly.

Another advantage this type of engine has over the ordinary two cycle gas engine 75 compressing the charge in the crank case is a higher carburation. Where the charge is drawn into the crank case, there is a relatively large clearance space permitting expansion and contraction of the gas and vapor contained therein. This results in a low suction. With my construction the clearance space is reduced to a minimum producing a better carburation due to the increased suction. With my improved engine, it is not necessary to make the crank 80 case gas tight, and by the use of a scotch yoke instead of a connecting rod, I am able 85 to construct a better balanced motor.

What I claim is:

1. A two cycle internal combustion engine comprising a cylinder, a piston therein, said cylinder having both ends closed and being provided with an inlet communicating with one end thereof and a bypass 90 communicating with both ends, a valve controlling the flow of gas to said inlet, a valve controlling the flow of gas through said bypass, a valve controlling the exhaust, and means to positively actuate all of said valves 95 and capable of varying the events. 100

2. A two cycle internal combustion engine comprising a cylinder, a piston therein, said cylinder having its crank end closed by a head and being provided with an inlet 105 communicating with the crank end and a bypass leading therefrom to the head end, a valve controlling the flow of gas to said inlet, a valve controlling the flow of gas through said bypass, a valve controlling the 110 exhaust, and means to positively actuate all of said valves and capable of varying the events.

In witness that I claim the foregoing I have hereunto subscribed my name this 26th 115 day of August, 1918.

JOHN W. BURNS.
